UNITED STATES PATENT OFFICE

159,563

COMBINED OIL BAR AND CABINET OR
SIMILAR ARTICLE

John O. Tews, Minneapolis, Minn., assignor to
Gray Company, Inc., Minneapolis, Minn., a cor-
poration of Minnesota

Application February 4, 1948, Serial No. 144,278

Term of patent 7 years

(Cl. D33—19)

To all whom it may concern:

Be it known that I, John O. Tews, a citizen of the United States, residing at Minneapolis, in the county of Hennepin, State of Minnesota, have invented a new, original, and ornamental Design for a Combined Oil Bar and Cabinet or Similar Article, of which the following is a specification, reference being had to the accompanying drawing, forming part thereof.

Figure 1 represents a perspective view, showing the front of the combined oil bar and cabinet or similar article of the present invention; and

Fig. 2 represents a top plan view.

The essential features of the design are shown in full lines.

I claim:

The ornamental design for a combined oil bar and cabinet or similar article, as shown and described.

JOHN O. TEWS.
